UNITED STATES PATENT OFFICE

2,522,295

AQUATIC DECOY

John H. Olsen, Whitefish Bay, Wis., assignor to
 Pulp Reproduction Company, Milwaukee, Wis.,
 a corporation of Wisconsin

Application December 29, 1945; Serial No. 638,214

1 Claim. (Cl. 43—3)

1

The present invention relates generally to improvements in the construction of aquatic decoys or the like, and relates more specifically to an improved floating type of hunter's decoy assemblage.

The primary object of my present invention is to provide an improved aquatic decoy adapted to be formed of relatively light and inexpensive material such as paper pulp, but which is exceedingly durable while also being well balanced and weighted so as to assume upright position.

I have heretofore developed a practical hunter's decoy comprising a body simulating an aquatic game bird and composed of a relatively thin shell of fibrous pulp having an open bottom recess and a relatively heavier buoyant base board sealing and confined with the body recess so as to provide a flat base surface substantially flush with the bottom of the body shell; the board also serving to balance and to maintain the decoy in upright position while floating. In manufacturing these prior aquatic decoys, the open bottom of the body was utilized for introduction of the pulp into the suction molds, and the sealing and righting boards had to be carefully inserted and snugly confined within the bottom recesses in order to prevent possible seepage of liquid into the hollow externally water-proofed pulp bodies, whereby softening or water-logging of the pulp and reduction in buoyancy might result. Thousands of these prior molded pulp decoys have however been sold and used with great success by sportsmen and others.

In order to avoid some work and cost of carefully inserting base boards and of providing a water-tight seal between these boards and the bodies, the open recess in the bottom of each decoy may be eliminated by providing the body with an integral base spanning and closing the bottom thereof, and by locating the pulp admission opening at the top and subsequently sealing this opening with a plug. Such a hollow pulp decoy must however be provided with balancing and righting means firmly attached to the integral pulp bottom closure, and if this pulp closure is pierced by suitable fastenings for the righting means the points of piercing must obviously be thoroughly sealed in order to positively prevent seepage of water into the hollow body through its bottom.

It is therefore a more specific object of the present invention to provide a decoy having a molded pulp hollow body provided with an integral pulp base spanning and closing the bottom thereof, and which is provided with effective bal-

2

aneing and righting means attached to the bottom so as to positively avoid possible leakage or seepage of liquid through the body structure.

Another specific object of this invention is to provide an improved aquatic decoy assemblage which may be conveniently manufactured and assembled at moderate cost, and which is most effectively protected against destruction due to abusive usage.

10: A further specific object of my invention is to provide an attractive and lifelike hunter's decoy, which will automatically assume upright or natural position when floating, and which may be readily duplicated and manufactured in large quantities.

Still another specific object of the invention is to provide an exceedingly strong and durable, but relatively light, decoy formed primarily of inexpensive moulded pulp in a manner whereby 20 its utility and effectiveness is enhanced to the maximum.

These and other specific objects and advantages of the improvement, will be apparent from the following detailed description.

25: A clear conception of the features constituting my present invention, and of the mode of constructing several types of aquatic decoys embodying the improvements, may be had by referring to the drawing accompanying and forming a part of this specification wherein like reference characters designate the same or similar parts in the various views.

Fig. 1 is a central longitudinal vertical section through a typical swimming duck decoy formed primarily of molded pulp, and embodying a wooden balancing base board applied in accordance with the present improvement; and

Fig. 2 is a transverse vertical section through the decoy of Fig. 1, taken along the irregular line 2—2.

40: While the invention has been illustrated herein as being advantageously applicable to a typical molded fibrous swimming duck decoy, it is not my desire or intent to unnecessarily restrict its utility by virtue of this limited embodiment, since the improved features may be more generally applied to various types of aquatic or floating decoys formed of relatively light material such as newsprint pulp or papier-mâché.

45: Referring to the drawing, the typical aquatic duck decoy shown therein comprises in general, a light but sturdy hollow shell or body 5 formed of molded fibrous pulp and having approximately uniform thickness throughout, the body 5 being 55 provided with an integral molded bottom 6 com-

pletely spanning and enclosing its lower portion; and a flat balancing or righting member such as a wooden board 7 snugly engaging the lower external surface of the body bottom 6 and being firmly secured thereto by a number of bolts or screws 8 piercing the bottom 6 and coacting with an internal anchoring strip or plate 9. The body 5 and bottom 6 are preferably produced in the well known type of suction molding machine, and in order to permit the pulp stock to be fed to the molds, the top of each body 5 is provided with a tapered hole or opening 10 which may subsequently be closed and effectively sealed by a fibrous pulp plug 11 cemented within the opening 10 flush with the body top surface.

While the righting board 7 which is preferably formed of relatively heavy but buoyant material such as wood, may be caused to snugly engage the body bottom 6 throughout its entire area by slightly dishing the lower surface of the bottom 6 during the molding operation, some provision must be made for eliminating possible leakage or seepage of liquid into the hollow body 5, if the fasteners or screws 8 are permitted to pierce the bottom 6. Such piercing is necessary in order to positively anchor the board 7 to the body 5 since the screws 8 if embedded in the relatively soft pulp alone, would not hold. I therefore provide the elongated internal anchoring plate 9 which is preferably formed of wood, or wood composition, or plastic; and in addition to this plate 9, I also provide a layer 12 of some suitable sealing and water-proofing substance such as asphalt, tar, or pitch, between the inner upper surface of the body bottom 6 and the anchoring strip 9. As shown, the opening 10 is made relatively small so as to enable ready and effective sealing, but the plate 9, while being narrower than the opening 10 to permit insertion therethrough, is of greater dimension in length than the opening 10 to provide maximum anchorage for the board 7.

During commercial production of these improved aquatic decoys, the hollow pulp bodies 5 and the integral bottoms 6 may first be produced in the usual manner with the aid of ordinary suction pulp molding machines. A layer 12 of hot molten asphalt, tar, or pitch may then be applied to the upper surface of the flat bottom 6 of each body 5, through the top opening 10, whereupon the anchoring strip or plate 9 may be inserted into the interior of the body 5 through opening 10 and embedded in the layer 12 of adhesive material while still in molten condition. Before the layer 12 has cooled sufficiently to become completely hardened, the outer board 7 and the screws 8 should be applied so as to clamp the board 7 and the anchoring plate 9 firmly in place and to simultaneously thoroughly seal the screw holes with water-proof substance; and it is to be noted that while some of the screws 8 are applied from the outside of the body 5, others may be applied and manipulated through the opening 10. After the righting board 7 and anchoring plate 9 have been thus permanently and rigidly attached to the body 5, the opening 10 may be sealed by a plug 11 so as to complete the decoy.

From the foregoing detailed description it will be apparent that my present invention provides an improved aquatic decoy which is simple and

durable in structure, and which is self-righting while floating. The improved decoy may be readily constructed of molded fibrous pulp with a hollow body 5 having an integral closure bottom 6, and the balancing and righting device may be firmly, neatly, and readily attached to the bottom 6 without danger of introducing leakage passages or spaces. The present improved assemblage positively eliminates necessity of providing extensive openings at the bottom of the decoy which is subject to prolonged exposure to the water, while still permitting permanent attachment of the righting board member 7 directly to the bottom 6; and the heavy layer 12 of waterproofing asphalt, tar, or pitch besides insuring a perfect seal, also strengthens the decoy structure and prevents the pulp base from becoming porous and soft. The improved decoys may be conveniently constructed and assembled from inexpensive materials and at moderate cost, and the completed structures besides being light and strong, automatically right themselves and present a highly finished life-like appearance.

It should be understood that it is not desired to limit this invention to the exact details of construction or to the precise mode of manufacture, herein shown and described, for various modifications within the scope of the appended claim, may occur to persons skilled in the art.

I claim:

An aquatic decoy comprising, a unitary hollow molded pulp body totally enclosed except for a local restricted opening formed in its top above its bottom, a buoyant righting board coacting with the lower outer surface of said body bottom, a layer of adhesive water-proofing material covering the entire upper inner surface of said bottom, an anchoring plate insertible within said body through said opening and coacting with said adhesive layer, means for directly fastening said board and plate together to partially embed the plate within the adhesive material, and a closure plug formed flush with the external bounding surface of the body for sealing said opening, said plate having a dimension greater than the width of said opening.
